US00D952462S

(12) **United States Design Patent** (10) **Patent No.:** **US D952,462 S**
(45) **Date of Patent:** **** May 24, 2022**

(54) **RING-PEEL-SEAL LINER**

(71) **Applicant:** **YNB SUPPLY (ASIA)**
CORPORATION, New Taipei (TW)

(72) **Inventor:** **Yen-Wu Yang**, New Taipei (TW)

(73) **Assignee:** **YNB SUPPLY (ASIA)**
CORPORATION, New Taipei (TW)

(**) **Term:** **15 Years**

(21) **Appl. No.:** **29/712,314**

(22) **Filed:** **Nov. 7, 2019**

(30) **Foreign Application Priority Data**

May 7, 2019 (CN) 201930217965.X

(51) **LOC (13) Cl.** **09-07**
(52) **U.S. Cl.**

USPC **D9/438**

Watts, LLP

(57) **CLAIM**

The ornamental design for a ring-peel-seal liner, as shown
and described.

DESCRIPTION

FIG. 1 is a perspective view of a ring-peel-seal liner showing
my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown represent unclaimed subject matter
and form no part of the claimed design.

1 Claim, 4 Drawing Sheets
